UNITED STATES PATENT OFFICE

LENA KANOWITZ, OF NEW YORK, N. Y.

DESIGN FOR A DRESS-HANGER BODY

Application filed January 10, 1930. Serial No. 34,088. Term of patent 14 years.

To all whom it may concern:

Be it known that I, LENA KANOWITZ, a citizen of the United States, residing at New York, in the county of New York and State of New York, have invented a new, original, and ornamental Design for a Dress-Hanger Body, of which the following is a specification, reference being had to the accompanying drawing, forming part thereof.

Fig. 1 is a side elevational view of a dress hanger body, showing my new design.

Fig. 2 is a top plan view of the same.

I claim:

The ornamental design for a dress hanger body, as shown.

In testimony whereof I have affixed my signature.

LENA KANOWITZ.
